[57] CLAIM

The ornamental design for a van body transition unit, as shown and described.

DESCRIPTION

FIG. 1 is a side elevational view of the van body transition unit, showing my new design.

FIG. 2 is a top plan view thereof.

FIG. 3 is a front elevational view thereof.

The appearance of the right-side is a mirror image of the left-hand side.

The broken lines represent a truck operator cab at the front of the intermediate portion and the truck box at the rear of the intermediate portion, but are not a part of the design.
